UNITED STATES PATENT OFFICE.

WALTER J. GADSBY, OF BOSTON, MASSACHUSETTS, ASSIGNOR TO THE
ROXBURY CARPET COMPANY, OF SAME PLACE.

DESIGN FOR A CARPET.

SPECIFICATION forming part of Design No. 13,111, dated August 1, 1882.

Application filed July 1, 1882. Term of patent 3½ years.

To all whom it may concern:

Be it known that I, WALTER J. GADSBY, of Boston, in the county of Suffolk and State of Massachusetts, have invented a new and original Design for Carpets, of which the following is a specification.

The nature of my design is fully shown in the accompanying photographic illustration.

The design is composed of a ground richly 10 ornamented by a variety of figures closely set together, and too varied and intricate to admit of a concise description, and floral and foliage designs arranged, as shown, on the ornamented ground.

I claim—

The design for a carpet, substantially as shown and described.

In testimony whereof I have signed my name to this specification, in the presence of two subscribing witnesses, this 27th day of June, A. D. 20 1882.

WALTER J. GADSBY.

Witnesses:

DAVID G. MELVILLE,
WILLIAM SCHMIDT.
